A. Wiswell.

Square.

Patented Sept. 7, 1832.

112X Jan 15 1809 259
Andrew Maxwell, of Boston, State of New Hampshire.

Letters Patent.

The subject referred to in these Letters Patent and making part of the same containing a description in the words of the said Andrew Maxwell himself of his improvement in the Tailor's improved square for delineating garments.

Be it known that I, Andrew Maxwell of Boston in the County of Roxbury
State of New Hampshire, have invented a new and useful improvement
in the Tailor's improved square, for delineating garments, which may
be made of Wood or metal, and that the following is a full description of
said square as improved by me.

All Tailors delineate their garments by the breast-measure divided and
cut a garment by mathematical proportion, it is necessary to use a square.

The breast-measure divisions have been obtained in a great variety of ways
but all in such a way, as to perplex the mind, and encumber the cutting-board.
My improvement is to have all the divisions divided and laid down on the square
so as to supersede the necessity of changing sides, of having a division across
the back, or strip of paper or sticks divided, as is now the practice.

On the outer edge of the long arm of the square in the first space
are the divisions of inches, and also the divisions of breast-measures.

In the third space is the number divided. In the fourth is the tail
to show the divisions and the number of the divisions.

The fifth space is the index. The rule of figures on the inside of the long
arm, commencing at four and ending at eight inches, is to get the width of
back and the shoulders by measuring from the center of the body, around
the shoulders to the center of the back again, and whatever number of inches
that is, find the same on the arm, and the back must be the width from
the number to the other of the square.

After a man's waist being marked around the square from the

center of the back, then the back of the arm must be dips under except the shoulder. The first and second appear in the short arm, in number into inches, thirds, halves, sixths, one twelfth of an inch and all the divisions of broad measure. The strip of tape then on the inner arm is to follow the measure on. To explain this more fully. The division from twelve to twenty four inches, are laid down on the square. If you will be work by twenty four inches, the half of that number may be found at twelve inches, the eighth at three inches, the sixteenth alone one and a half inches, the thirty second at three quarters of an inch. The thirty second right index (on the short arm), the eighth at four inches, the twelfth at two inches, the twenty fourth at one inch, and in this way you may find the division of twenty four, or any other number down to twelve.

And when a tailer understands the principle of this square he may cut a garment by it of larger or smaller sizes than is laid down here.

For instance the divisions of halves are one half inch to a size, the fourth, one fourth of an inch to a size, the eighth are one eighth of an inch to a size, the thirds are one third of an inch the eight and eighth of an inch, the twelfth, one twelfth of an inch & the square is twenty four inches long, the long arm and the short arm are ten inches long and are one and an half inches wide, made of box wood. The box wood to be the most convenient size & the best material to make them of, but they may be made of metal, or any other hard wood, and of any convenient size, some eight by twelve inches.

In testimony that the above is a true specification of my own improvement as above described. I have hereunto set my hand, this second day of May in the year of our Lord one thousand eight hundred and thirty two,

Witnesses,

Joseph French,
Jonathan Farmer 3
